UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINE-CASTING MACHINE.

1,111,096.

Specification of Letters Patent. Patented Sept. 22, 1914.

Application filed May 8, 1911. Serial No. 625,725.

To all whom it may concern:

Be it known that I, JOHN R. ROGERS, a citizen of the United States, and a resident of Brooklyn, county of Kings, and State of New York, have invented a new and useful Improvement in Line-Casting Machines, of which the following is a specification.

My invention has reference to linotype machines, in which matrices carrying one or 10 more letters to be independently used are stored in a magazine and are delivered singly by the action of finger-keys representing the various characters, then assembled in line, the line transferred to the face of a slotted 15 mold, the mold filled with molten metal to produce the linotype, and the matrices finally returned to the magazine from which they started.

More particularly the invention relates to 20 the employment of a number of fonts or sets of matrices representing different sizes or styles of type, in such manner that any font may be brought into action at will; so that matter may be produced with faces represented by the matrices in any one magazine, or by a combination of faces represented by the matrices in two or more magazines. For this purpose I employ a series of shiftable magazines and means whereby any selected one thereof may be brought into operative relation to the other parts. Specifically and preferably I use vertical magazines which are suspended at their upper ends from a horizontally sliding frame, this 30 particular arrangement affording special advantages, not only because of the easy manipulation of the magazines as a whole and their proper coördination with the other operative devices, but also as it enables 35 me to effect the easy removal of the individual magazines from the frame and the substitution of others therefor.

In the accompanying drawings, I have shown my invention as applied to a linotype machine of the general character and style illustrated in my former Letters Patent No. 734,096, granted July 21, 1903, but obviously it may be similarly used in connection with type-setting machines, or in fact any kind 45 of typographical machine, and I therefore desire it to be distinctly understood that I do not limit myself to any specific form or embodiment except in so far as such limitations are specified in the claims.

Referring to the drawings: Figure 1 is a

perspective view of the machine referred to, having my invention applied thereto; Fig. 2 is a right-hand elevation of the same; Fig. 3 is a front elevation on an enlarged scale of the magazines, etc.; Fig. 4 is a vertical section taken substantially on the line 4—4 in Fig. 3; Fig. 5 is a detached view of the magazine frame and its supporting and moving means; Fig. 6 is a sectional detail taken substantially on the line 6—6 of Fig. 5; and Fig. 7 is a view illustrating the mode of removing or replacing an individual magazine.

The general organization of the machine is or may be substantially like that shown and described in my Letters Patent, No. 734,096, and comprises a main frame A, finger-key levers D, which control the release of the matrices in the magazine B, from which they are delivered in proper order and assembled with spacers and then transferred to the casting mechanism where the linotype is formed. The assembled line is then raised by the elevator K to the top of the machine, at which point the spacers are separated therefrom and restored to their magazine J. The matrices are caused to pass along the distributor bar X, from which they drop and are returned to the magazine B. All of these parts are old in the art, and operate in substantially the same manner as the parts similarly lettered in my said patent. Certain features different in function and mode of operation are now to be described.

In the previous machine a single magazine only is shown, and in order to permit the employment of a plurality of faces my present invention provides a plurality of magazines, B, B, B, etc., which may be shifted so as to bring any selected one thereof into operative relation to the keyboard and assembling devices. In the drawings I have illustrated four such magazines, but obviously this number may be increased or diminished as desired. The magazines B, B, B, are preferably vertically disposed and are supported and suspended at their upper ends in the horizontally shiftable frame M. The frame M in turn is supported by the frame brackets A¹, A¹, and is slidably connected thereto in any suitable manner, as for instance in the grooves A², see Fig. 6. If desired, rollers M¹, M², or other anti-friction devices, may be interposed between the frame and the brackets. The means for

shifting the frame M and the supported magazines B, B, B, so as to bring any selected one of them into operative position will be subsequently described. Each of the 5 magazines B is provided at its lower end with matrix controlling devices or escapements C, C, C, see Fig. 4. The escapement C is of the usual form and is designed to permit the release of the matrices one at a 10 time. Generally speaking, it consists of a pivoted lever carrying two pawls or dogs which are alternately projected into the magazine. A spring bears upon the lever so as normally to hold one of the pawls in 15 the magazine channel and thereby to retain the matrices therein. The position of the escapement is reversed and controlled by the bail d, which is operated from the finger-lever D in the customary manner. The specific 20 form of escapement constitutes no part of my present invention, and the one described is of the general type customarily employed in linotype machines.

Referring particularly to Fig. 4, it will be 25 seen that the escapement levers C, C, are mounted in appropriate position, so that the horizontal shifting of the magazines brings the escapements of the selected one into proper operative relation to the single bank 30 of escapement bails d. This feature is of importance for the reason that it obviates the necessity for special devices, either to lock the matrices in the magazines during shifting, or to bring the matrices of the selected 35 magazine into operative relation to the bails d.

In order to effect the horizontal shifting of the magazines, I employ a rack and pinion device, and preferably provide the frame 40 M with two racks M¹, M², in order that the frame may be uniformly acted upon and the magazines shifted in proper parallel relations. Meshing with the racks M¹, M², are 45 two pinions N, N, fast upon the shaft N¹, which is supported in the framework. At one end of the shaft N¹ is also mounted a gear N² which meshes into the actuating sector N³ fast upon the short rock shaft N⁴, which is suitably located in the frame A. 50 At the other end of the rock shaft N⁴ is mounted the handle N⁵ in convenient position to be manipulated by the operator at the keyboard. It will be seen that this arrangement and construction permits any 55 selected magazine to be brought into operative relation to the other parts, including the proper engagement and registration of its escapement levers C, C, with the single bank of bails d. I also provide suitable 60 means whereby the selected magazine when shifted is locked in operative position. These means may be of any desired construction, and in the form shown comprise the ordinary locking lever N⁶ pivoted to the 65 operating handle N⁵ and adapted to engage

with suitably located notches in the fixed locking piece N⁷.

In order to permit the independent removal and replacement of the individual magazines B, B, B, with relation to the frame M, I preferably form the latter with grooves M¹, M², etc., which engage the upper ends of the magazines B, B, B, and thereby sustain them in suspended position. These grooves M¹, M², etc., are located transversely to the direction of movement of the frame M, and it will be obvious that the individual magazines may be readily slid into and out of their proper position, see particularly Fig. 7.

By this construction and arrangement I have provided simple means whereby any selected magazine may be brought into proper relation to the other parts, and moreover, it is possible to remove any individual magazine and to substitute another therefor. Thus it will be obvious that I readily and quickly obtain any desired change of font or face, or any desired mixture thereof. In the present application I have simply illustrated a preferred embodiment of my invention, but obviously many changes and variations such as will suggest themselves to those skilled in the art may be made therein without departing from its spirit.

Having thus described my invention, its construction and mode of operation, what I claim and desire to secure by Letters Patent of the United States is as follows:

1. In a typographical machine, the combination of a distributing mechanism, a plurality of magazines and a supporting frame therefor provided with means to engage and support the magazines by their upper ends so as to hold them in suspended condition, the said frame being mounted in the framework of the machine at a point immediately adjacent the distributing mechanism and movably arranged so as to bring any selected magazine into operative relation thereto.

2. In a typographical machine, the combination of a distributing mechanism, a plurality of magazines, a supporting frame therefor and mounted in the framework of the machine at a point immediately adjacent the distributing mechanism and provided with means to engage and support the magazines by their upper ends so as to hold them in suspended condition, and means for moving said frame bodily in a horizontal direction to bring any selected magazine into operative position.

3. In a typographical machine, the combination of distributing mechanism, a plurality of magazines and an overlying supporting frame therefor mounted in the framework of the machine at a point immediately adjacent the distributing mechanism,

the said magazines being each slidably supported by their upper ends in said frame so as to be independently removable therefrom.

4. In a typographical machine, the combination of a distributing mechanism, a magazine and an overlying supporting frame therefor mounted in the framework of the machine at a point immediately adjacent the distributing mechanism, said magazine being slidably supported by its upper end in said frame so as to be removable edgewise therefrom.

5. In a typographical machine, the combination of a distributing mechanism, a supporting frame mounted in the framework of the machine at a point immediately adjacent the distributing mechanism and provided on its under side with a grooved portion and a magazine slidably supported

by its upper end in said grooved portion so as to be readily removable from the frame.

6. In a typographical machine, the combination of the magazines B, the sliding frame M to support the magazines and provided on its upper side with racks M², the transverse rock shaft N¹ provided with the pinions N meshing into the racks M², and the actuating pinion N², and the manually operated sector N³ meshing into the actuating pinion.

In testimony whereof I hereunto set my hand this third day of May, 1911, in the presence of two attesting witnesses.

JOHN R. ROGERS.
